W. E. SHORE

BURNER FOR OIL BURNING FURNACES

Filed July 31, 1922

Inventor
William E Shore
by H. J. Dennison
Atty

UNITED STATES PATENT OFFICE.

WILLIAM E. SHORE, OF NEW YORK, N. Y.

BURNER FOR OIL-BURNING FURNACES.

Application filed July 31, 1922. Serial No. 578,646.

To all whom it may concern:

Be it known that I, WILLIAM E. SHORE, a subject of the King of Great Britain, and resident of the city and State of New York, 5 in the United States of America, have invented certain new and useful Improvements in Burners for Oil-Burning Furnaces, described in the following specification and illustrated in the accompanying drawings, 10 that form part of the same.

The principal objects of this invention are, to enable the burning of a nebulized oil fuel without the deleterious effect of coking in the nozzle and to ensure the complete combustion of the fuel producing the highest possible temperatures.

The principal feature of the invention consists in conducting the nebulized fuel through a tubular conduit to a diverging 20 heated member and directing a flow of air to effectively insulate the delivery conduit from said heated member whereby the nebulized fuel is discharged from the conduit into the diverging member to effect the expansion thereof prior to its combustion.

In the drawings, Figure 1 is a longitudinal section of my improved burner taken on the line 1—1 of Figure 2.

Figure 2 is a transverse sectional view of 30 the nozzle taken on the line 2—2 of Figure 1.

Many different forms of devices have been conceived for atomizing fuel oils and in practically all instances the fuel is projected directly into the combustion chamber from 35 an atomizing nozzle. The present invention is herein shown as applied to a conduit conducting nebulized fuel to the combustion chamber, the means for nebulizing the fuel not being shown as this invention is separate 40 from such nebulizing means.

In the construction herein shown the tubular conduit 1 leads from a suitable nebulizing apparatus and discharges the nebulized fuel from the open end 2.

Surrounding the conduit 1 is a cylindrical member 3 spaced therefrom by the longitudinal webs 4 supported on the collars 5 and 6 encircling the conduit. The member 3 is open at both ends so that the air 50 will flow readily therethrough.

The collar 6 is formed with a conical outward end 7 which intercepts the longitudinal flow of air from the opposite end of the member 3 diverting it in an outward direction.

The supporting webs 4 extend beyond the

collar 6 and cone end 7 and support a conical-shaped member 8 which is spaced from the cone end 7 but forms a continuation thereof. The space between the members 7 and 8 forms an air port 9 which preferably flares outwardly, that is, toward the outer side of the cone and in the direction of the member 3 and is thus open to receive a certain amount of air flowing through the member 3.

Longitudinal slots 10 are formed in the member 8 to admit further supply of air.

In the use of this device the conduit 1 is connected with a suitable form of nebulizer and the nebulized fuel is forced therethrough, being discharged at the end 2 into the combustion chamber of the furnace. The member 8 extends into the combustion chamber of the furnace and the cylindrical portion 3 extends through the furnace wall and forms an air duct to direct a flow of air into the furnace around the member 8. The natural draught of the furnace creates a strong flow of air through the cylindrical member 3 which thus absorbs the majority of the heat transmitted to the conduit 1 from the incandescence of the combustion chamber and this occurs to such an extent that coking of the fuels in passage through the conduit is absolutely avoided.

The combustion of the nebulized fuel is very greatly enhanced by the arrangement of the cone member 8. The rush of air through the cylindrical member 3 is directed in an outward direction by the surface of the cone and such flow of air past the larger end of the cone creates a suction which causes the nebulized fuel discharged from the conduit 1 to expand. This action is greatly assisted by the incandescent heat of the combustion chamber and the flame and air is mixed with the nebulized fuel by passing through the port 9 and the slots 10. The cone member 8 will naturally become very hot owing to its proximity to the flame but it is insulated from the member 7 and therefore from the members 1 and 3 by the air port 9. The conduit will therefore be maintained at a comparatively low temperature and such as will not cause coking of the fuel.

The result of the use of a device such as described is that a very low grade of fuels may be used without danger and they will maintain a constant condition of temperature.

What I claim as my invention is:—

1. In a burner for oil burning furnaces, the combination with the furnace front having an opening therethrough, of a delivery conduit for directing vaporized fuel through said opening, a conical member having its smaller circular end engaging the delivery end of said delivery conduit and flaring outwardly and extending into the combustion chamber, the smaller end of said conduit being insulated from the larger end to obviate the transference of a coking heat to the delivery conduit, and a conduit encircling said delivery conduit and directing a flow of air against the exterior of said conical member.
2. In a burner for oil burning furnaces, the combination with the furnace front having an opening therethrough, of a cylindrical member arranged in said opening being open at the ends and having radial longitudinal webs extending inwardly, collars supported by said webs, a fuel discharge tube supported in said collars, and a flaring

conical member supported by said longitudinal webs to project into the combustion chamber and to direct the inflowing current of air divergently from the discharge end of the fuel tube. 25

3. In a burner for oil burning furnaces, the combination with the furnace front having an opening therethrough, of a cylindrical member open at the ends arranged in said opening and having inwardly extending radial webs, a collar supported by said webs at the inner end having a conical flare adapted to direct the flow of air outwardly, a conical-shaped member spaced from said conical member and supported by the forwardly extending radial webs and adapted 30 to project into the combustion chamber and having a plurality of longitudinal slots therein, and a fuel vapor supply pipe supported in said collar and discharging vapor fuel into the conical extensions from said collar. 35
